UNITED STATES PATENT OFFICE.

BENJAMIN D. STEVENS, OF BURLINGTON, VERMONT, ASSIGNOR TO HIMSELF, AND BENJAMIN H. CHEEVER, OF LOWELL, MASSACHUSETTS.

ROLL FOR LOOM-TEMPLES.

SPECIFICATION forming part of Letters Patent No. 399,445, dated March 12, 1889.

Application filed October 15, 1888. Serial No. 288,106. (No model.)

To all whom it may concern:

Be it known that I, BENJAMIN D. STEVENS, of Burlington, in the county of Chittenden, State of Vermont, have invented a certain new and useful Improvement in Rolls for Loom-Temples, of which the following is a description sufficiently full, clear, and exact to enable any person skilled in the art or science to which said invention appertains to make and use the same, reference being had to the accompanying drawings, forming part of this specification, in which—

Figure 1 is an end elevation of my improved temple-roll; Fig. 2, a like view showing the opposite end of the roll; Fig. 3, a vertical longitudinal section taken on the line *x* *x* in Fig. 1, and Fig. 4 a sectional view illustrating certain details of construction.

Like letters and figures of reference indicate corresponding parts in the different figures of the drawings.

My invention relates to that class of loom-temple rolls which are provided with teeth or points; and it consists in certain novel features, as hereinafter fully set forth and claimed, the object being to produce a more effective and otherwise desirable device of this character than is now in ordinary use.

The nature and operation of the improvement will be readily understood by all conversant with such matters from the following explanation.

In the drawings, *A* represents the body of the roll, which is of the ordinary form and construction, excepting as hereinafter described, and is adapted to be disposed in the temple in the usual manner. The body *A* is provided with a series of longitudinally-arranged equidistant grooves, *z*, preferably eight in number, the bottom of said grooves being inclined, as shown in Fig. 3, making them of greater depth at one end of the roll than they are at the opposite end, as illustrated by Figs. 1 and 2, respectively. Metallic plates *m*, adapted to enter said grooves, are provided on one edge with teeth or points *i*, the opposite edge of said plates being beveled longitudinally to conform to the inclined bottoms of the grooves *z*. Each end of the plates *m* is beveled, as shown at *v* in Fig. 2.

Each end of the body of the roll is reduced, forming an annular shoulder, *t*, (see Fig. 4,) and disposed on said reduced portions is a tight-fitting metallic ring, *f*.

In the use of my improvement the plates *m* are disposed in the grooves *z* and the rings *f* driven onto the reduced ends of the body *A* until they engage the beveled ends *v* of said plates and secure the same firmly in position in said grooves, said beveled ends *v* preventing the plates from being moved vertically in the grooves. By withdrawing a ring *f* slightly on one end of the roll and forcing forward the ring on the opposite end thereof it will readily be seen that the plates can be moved longitudinally in the grooves, thereby adjusting the teeth thereon vertically in relation to the surface of the roll in a manner that will be readily understood by all conversant with such matters without a more explicit description. The temple is thus rendered much more effective in its operation, as the teeth may be readily adjusted to suit the character of the cloth which is being woven.

Having thus explained my invention, what I claim is—

1. A loom-temple roll provided with a series of longitudinal grooves having inclined bottoms and serrated plates disposed therein, an edge of each of said plates being inclined to conform to the bottom of said grooves, substantially as set forth.

2. The combination of a roll having a series of grooves in its body provided with inclined bottoms, serrated plates disposed therein and having correspondingly-inclined edges, whereby they may be adjusted vertically when moved longitudinally, and rings for securing said plates in position in said grooves, substantially as described.

3. A roll provided with a series of longitudinal grooves having inclined bottoms, plates fitted to slide in said grooves, the outer edges of said plates being provided with teeth or points and the inner edges inclined to conform to the bottoms of said grooves, and adjunctive mechanism for detachably securing the plates in position, whereby the teeth or points may be adjusted vertically in relation

to the surface of the roll as the plates are moved longitudinally, substantially as set forth.

4. The combination of a roll having reduced ends and provided with a series of longitudinal grooves having inclined bottoms, plates provided with beveled ends and fitted to slide in said grooves, the outer edges of said plates being serrated and the inner edges inclined to conform to the bottoms of the grooves, and rings adjustably disposed on the reduced ends of the roll in engagement with the beveled ends of the plates, substantially as and for the purpose set forth.
- 15 5. In combination, the body A, having re-

duced ends and provided with grooves z, having longitudinally-inclined bottoms, in combination with the serrated plates m, provided with beveled ends v, and having their inner edges inclined to conform to the bottoms of said grooves, and the rings f, disposed on the reduced ends of said body and adapted to engage the ends v of said plates and secure the same in position in said grooves, substantially as described.

BENJAMIN D. STEVENS.
